CLAIM

The ornamental design for a utility tote panel insert, as shown and described.

DESCRIPTION

FIG. 1 is a rear view of a utility tote panel insert according to a first embodiment of our new design, wherein the utility tote panel insert is in a folded configuration;

FIG. 2 is a front view thereof;

FIG. 3 is a top view thereof;

FIG. 4 is a bottom view thereof;

FIG. 5 is a left-side view thereof;

FIG. 6 is a right-side view thereof;

FIG. 7 is a top perspective view of the utility tote panel insert of FIGS. 1 to 6, but wherein the utility tote panel insert is in a flat or unfolded configuration;

FIG. 8 is a bottom perspective view thereof;

FIG. 9 is a top view thereof;

FIG. 10 is a bottom view thereof;

FIG. 11 is a rear view thereof;

FIG. 12 is a front view thereof;

FIG. 13 is a left-side view thereof, the right side view being a mirror image thereof.

FIG. 14 is a rear view of a utility tote panel insert according to a second embodiment of our new design, wherein the utility tote panel insert is in a folded configuration;

FIG. 15 is a front view thereof;

FIG. 16 is a top view thereof;

FIG. 17 is a bottom view thereof;

FIG. 18 is a left-side view thereof;

FIG. 19 is a right-side view thereof;

FIG. 20 is a top perspective view of the utility tote panel insert of FIGS. 14 to 19, but wherein the utility tote panel insert is in a flat or unfolded configuration;

FIG. 21 is a bottom perspective view thereof;

FIG. 22 is a top view thereof;

FIG. 23 is a bottom view thereof;

FIG. 24 is a rear view thereof;

FIG. 25 is a front view thereof; and,

FIG. 26 is a left-side view thereof, the right side view being a mirror image thereof.
